UNITED STATES PATENT OFFICE

GEORGE W. SWIFT, JR., OF BORDENTOWN, NEW JERSEY, ASSIGNOR TO GEORGE W. SWIFT, JR., INC., OF BORDENTOWN, NEW JERSEY, A CORPORATION OF NEW JERSEY

SHEET-FEEDING MEANS

Application filed November 28, 1927, Serial No. 236,161. Renewed April 16, 1929.

This invention relates more especially to sheet feeding machines of the type shown and described in U. S. Patent No. 1,643,646 issued in my name under date of September 27, 5 1927, and U. S. Patent No. 1,647,819 issued in my name under date of November 1, 1927.

The primary object of my invention is to provide mechanism of improved construction for separating successive sheets of relatively 10 stiff material from the bottom of a pile and into the path of suitable sheet-feeding devices such, for example, as those shown and described in my above-identified U. S. patents.

15 One of the objects of my invention is to provide simple and effective means of improved construction for accurately and rapidly separating successive sheets of cardboard or the like from the bottom of a pile.

20 Another object of my invention is to provide an improved arrangement and adjustment of the vertical guide assemblies which form the delivery throat for a pile of sheets from which successive sheets are to be separated. Heretofore it has been necessary for 25 the operator of a machine of this character to move inwardly or outwardly with respect to said machine to enable him to conveniently handle sheets of different sizes. According 30 to my present invention, it is possible for the operator to manipulate sheets of any desired size while he remains in one and the same position with respect to the machine.

In the drawings which illustrate a preferred embodiment of my invention in an adaptation to a box blank feeding machine,

Figure 1 is a vertical section of a cardboard sheet-feeding machine provided with my improved sheet-separating mechanism, parts 40 being broken away and parts shown in side elevation.

Figure 2 is an enlarged top plan view of a rear end portion of the same, parts being broken away.

45 Figure 3 is an enlarged vertical section of the sheet-separating mechanism, parts being broken away.

Figure 4 is an enlarged vertical section similar to Figure 3 with parts shown in 50 changed positions.

Figure 5 is a section on the line 5—5, of Figure 2.

In Figure 1 of the drawings, knurled feed rollers A and B of a slotting or blanking-out machine, are journaled in side frames 3, 3, 55 of which only one is shown on the drawings. Journaled within the side frames 4, 4, are parallel shafts 5 and 6 to which are keyed sprocket wheels 7 and 8. Adjustably mounted on a stay shaft 9 are laterally-spaced bent 60 levers 10 within which are journaled sprocket wheels 11. Running over the sprocket wheels 7, 8 and 11, are endless conveyor chains 12 which are supported by longitudinal track-bars 13, extending substantially across the 65 space between said sprocket wheels 7 and 8. Connected with the conveyor chain 12 are sheet-propelling devices adapted to loosely but positively confine the rear edges of sheets which are separately and successively removed from the bottom of the pile. Each of 70 said devices comprises a sheet-engaging member or pusher which is adapted to push a sheet forward and a sheet-confining or retaining member which is articulately connected thereto and thereby adapted to be moved to and fro between a position in which it retains a sheet against displacement from engagement with the sheet-propelling member and a position in which said sheet is left 75 unhampered to move out of engagement with said sheet-propelling member. Thus, upon the oppositely-extended ends of one or more of the pintles 16 of chain 12, are pivotally mounted the laterally-spaced arms of 80 each of a plurality of sheet-engaging members 17 pivotally connected by pins 19 to the corresponding arms of sheet-confining or retaining members 20. Coaxially arranged 85 pins 22 carried by each sheet-confining member 20, serve as journals for laterally-spaced cam-rollers 23, 23. Presented upwardly from the sheet-engaging member 17 is a lug or shoulder 24 which is provided with a rearwardly beveled upper surface 25 to accommodate the to and fro movements of a flange or plate 26 which is carried by the sheet-confining member 20. Said flange 26 in its sheet-confining position, is adapted to overhang the 90

95

100

rear edge of a sheet resting upon the lug or shoulder 24.

Operating cams

5 As shown and described in my above-identified U. S. Patent No. 1,647,819, laterally-spaced cam-tracks are provided for imparting relative movements to the members of each sheet-propelling device to confine the 10 rear edge of a sheet while said sheet is being fed from the pile, a single additional cam-track being arranged to constrain the movements of said members after a sheet has been released and during their return into position to engage the rear edge of the next sheet 15 to be fed.

Referring to Figure 1 of the drawings, it will be seen that the laterally-spaced cam-tracks 27, 27, have their left hand ends disposed slightly below and to the left of the axis of sprocket wheel shaft 5 and nearer to 20 said axis than the links of chain 12 passing around the sprocket wheels 7, 7. From this point, said cam-tracks extend outwardly and 25 upwardly around the axis of shaft 5, and above the plane of the horizontal path of chains 12, 12, reaching their highest elevation at a point adjacent to the rear edge of the 30 pile of sheets as shown in Figure 1. From this summit said cam-tracks drop away on an incline to a plane below the horizontal path of said chains 12, 12, and terminate at their 35 forward ends adjacent to the sprocket wheels 8, 8. It will be understood from this description that as the sheet-propelling members 40 pass around the periphery of sprocket wheels 7, 7, the cam rollers 28 are brought into engagement with the depending ends of cam-tracks 27 and become gradually 45 displaced thereby until as said members reach the position shown in the upper left hand portion of Figure 1, they are fully extended with 50 respect to each other and together are tilted with respect to the upper horizontal path of chains 12, 12. It is just prior to assuming this 55 position that the flange 26 is moved into position to overhang the rear edge of the bottom sheet which has become partially separated from the pile in the manner fully shown and 60 described in my above identified Patent No. 1,647,819. The subsequent forward movement of the lug or shoulder 24 toward the right thereupon completes the separation of the sheet and delivers the forward edge thereof to feed rollers A and B. Suitable means 65 for flexing the members of the sheet-engaging devices to free the rear end of a sheet after the forward end thereof has been gripped by 70 rolls A and B, may be provided as follows.

60 A cam-track 28 has one end thereof disposed above the right hand end of one of the parallel cam-tracks 27 and in suitable position to have its inner edge engage the cam roller on that side as it leaves the cam-track 27. Immediately after leaving the cam-track

27, said cam roller is depressed by a downwardly protruding portion 28a of cam-track 28 in such a way as to flex the sheet-propelling members for the purpose of releasing the rear edge of the sheet. Thereupon, said sheet continues its forward movement under the action of feed rolls A and B. As shown in Figure 1, the cam-track 28 extends downwardly adjacently to but deviating gradually from the path of one of the chains 12 and thence in a circular arc around and outside of the periphery of one of the sprocket wheels 11. A rearwardly extending portion of track-bar 28 is inclined upwardly toward the sprocket wheel 7 around which it extends in 75 an arc and terminates adjacent to the summit of track-bars 27, 27. An arcuate strap 31 which, as shown in the left hand portion of Figure 1, extends upwardly and around the periphery of sprocket wheel 7, is adapted to 80 slidably engage the gripper flange 26 and thereby to gradually straighten out the flexed sheet-propelling members as they approach sheet-engaging position.

Any suitable feed table or platform may be 85 provided between the side frames 4, 4, in approximately the same horizontal plane as the bite of the delivery rollers A, B. As shown in the accompanying drawings this feed table is formed in spaced section 35, 35, 35, one or 90 more of the intermediately arranged sections being slightly depressed to better accommodate the carriage upon which the feeding off devices are mounted. The spacing between 95 the table sections 35, 35, 35, is to accommodate 100 the forwardly-moving sheet-feeding devices described above.

Sheet feeding mechanism

The side frame 4, 4 have formed in their 105 upper faces T-shaped slots 36 shown best in Figure 2, in which engage the shouldered nuts on bolts 37 which pass through lateral guide flanges 38 of the side brackets 40 of an adjustable sheet feeding frame. The side brackets 110 40 may thus be secured in any desired adjusted position upon the machine side frames. These side brackets 40 are connected by a squared bar 41 extending from side to side of the machine and supporting above the table 115 the rear guide frames and controlling devices of the pile or column of sheets, hereinafter described. Arranged in alignment but spaced from each other across the feed table or platform, are a plurality of supports for holding 120 the rear end of the pile at a greater elevation than the forward end thereof. Each of said supports, in the preferred embodiment of my invention, comprises a base flange 42 which is secured to one or another of the laterally-spaced table sections 35, 35, 35, by means of bolts 43, an intermediate upright portion 44, and a forwardly-presented shelf 45 which projects below and in front of the squared bar 41. The laterally-spaced ends of shelves 130

45, 45, 45, are arranged in substantially the same vertical planes as the laterally-spaced edges of table sections 35, 35, 35, for the purpose of permitting the passage of the sheet-propelling devices described above. The side brackets 40 are provided with bearings 46 within which is oscillatably mounted a power-driven rock-shaft 47. Mounted on rock-shaft 47 are the split hubs 48, 48, of laterally-spaced lever-arms 49, said split hubs being provided with cap screws 50, 50, for releasably clamping the lever arms 49 in any adjusted position on said rock-shaft. Each of said lever arms 49 is pivotally connected by means of a pintle 51 to the bifurcated lug 52 of a plate or flange 53, a pusher plate 54 being secured along its rear edge to each pair of flanges 53, 53. As shown in Figures 3 and 4, the pusher plates 54, 54, 54, have their forward edges slidably 10 engaging the upper surfaces of shelves 45, 45, 45, and are thus brought into engagement with the rear edges of successive bottom sheets of the pile P for successively separating said bottom sheets from the pile. A leaf 15 spring 54^a which is secured at one end to each pusher plate 54, has its other end in slidable engagement with the under surface of squared bar 41 for retaining plate 54 in yieldable sliding engagement with the upper surface 20 of shelf 45. Secured to the rear face of the squared bar 41, are a series of plates or brackets 55, 55, 55, said brackets being respectively arranged between the vertical planes corresponding to the laterally-spaced ends of 25 table sections 35, 35, 35. Each plate or bracket 55 is provided at its lower end with spaced bearing lugs 56, 56, for oscillatably supporting the trunnioned ends 57, 57, of a rectangular block 58. Secured to the under side of 30 each block 58 is a flat blade 59 which is fastened at its rear end to a lower toggle link 60. Said lower toggle link 60 is connected by a pintle 61 to an upper toggle link 62, the last-mentioned link being suspended by its upper 35 end from a pin 63 carried by a rearwardly-presented bifurcated arm 64 which is provided with a split hub 65 and releasably clamped on the rock-shaft 47 by means of screw bolts 66. It will be understood from 40 the above description that as the flat blade 59 is oscillated on the trunnions 57, 57, by radial arm 64, it will be moved to and fro between the positions shown respectively in Figures 3 and 4. According to Figure 3, a partial forward movement of the pusher plates 54, 54, 54, is followed by an upward movement of the lifting blades 59, 59, 59, the latter movement serving to elevate the rear end of the 45 pile from the forwardly-displaced bottom sheet. Said bottom sheet is thus left free along its rear edge for the unobstructed forward movement of the sheet-propelling device as indicated in Figure 3. Thereupon the 50 bottom sheet is separated from the pile and

fed forwardly through the delivery throat to be presently referred to.

By referring now to Figures 1 and 2, it will be seen that the front edge of the pile of sheets rests upon the forward portion of table sections 35, 35, 35, and against the lower inclined faces 80^a of the vertical guides 80. These guides 80 are vertically adjustable in the channelled rear faces of brackets 100 which are transversely adjustable upon a frame bar 105. 101 are adjusting screws mounted in guide members 80 and engaging brackets 100 for adjusting the width of the delivery throat between the lower ends of guides 80 and the delivery end of the table or platform. In the drawings two sets of front guides 80 are shown arranged at equal distances from the central vertical longitudinal plane of the machine although it will be understood that any desired number of these guides may be employed.

The lower end of each of the front guides 80 carries two yieldably mounted sheet engaging and controlling devices which are supported directly above the delivery end of the feed table or platform and form therewith the controlling delivery throat. These devices are shown, described and claimed in U. S. Patent No. 1,643,646, granted in my name under date of September 27, 1927.

Mounted in front of the sheet-controlling delivery throat is an eccentrically supported semi-cylindrical caliperating gate member 125 which is carried by a bearing shaft 126 journaled in brackets 127. Pins 128 mounted in shaft 126 are engaged by springs 129 connected with angular brackets 130 to yieldably retain the caliperating member 125 in normal position. It will be understood that the caliperating member 125 may be adjusted toward and away from the plane of feed with guide member 80 through the action of screw 101.

Means for adjusting the front guide assemblies

As indicated in Figures 1 and 2, the transverse bar 105 upon which the front guide assemblies are mounted, may be carried by laterally-spaced brackets 131 which are provided with base flanges 132 slidable on the top-rails 140 which extend longitudinally of the machine. Extending through the base flanges 132 and T-slots 36, are bolts 133 which are provided with nuts 133^a for securing the side brackets 131 in position. The oppositely-arranged side brackets 131 are provided with pedestals 134 to the top of which the transverse bar 105 is bolted. Journaled in the pedestals 134 is a cross-shaft 135, said cross-shaft being provided with axially-spaced gears 136 which mesh with laterally-spaced racks 137. Hand-wheels 138 are secured to the opposite outer ends of the cross-shaft 135, for effecting a ready adjustment

of the front guide assemblies toward and away from the transverse supporting frame which carries the sheet-feeding mechanism at the rear end of the feed-board. For this purpose, the bolts 133 are loosened to permit the flanges 132 to slide over the top rails 140, said bolts being again tightened up after the desired adjustment has been made.

I claim:

1. In a sheet feeding machine, the combination with means for supporting the rear end of a pile of sheets, of means movable into and out of engagement with the rear edges of successive bottom sheets in said pile for imparting relative forward movements thereto, a lever movable into and out of position to elevate the rear end of the remainder of said pile, a rock-shaft, a toggle link connection between said rock-shaft and said lever, and feed-off mechanism adapted to engage the rear end of the forwardly-displaced bottom sheet.

2. In a sheet feeding machine, the combination with a shelf for supporting the rear end of a pile of sheets, a sheet pusher movable above said shelf at the rear of said pile for imparting relative forward movements to successive bottom sheets of said pile, means for elevating the rear end of the undisplaced remainder of said pile, said means including a rock-shaft, a pivotally-mounted lever movable into and out of engagement with the pile remainder, and toggle links connecting said rock-shaft to said lever, said lever being rigidly joined to one of said toggle links, and feed-off mechanism provided with means movable into engagement with the rear end of the forwardly displaced bottom sheet.

3. In a sheet feeding machine, the combination of guides for a pile of sheets, a shelf supporting one edge of said pile, means for displacing successive individual sheets forwardly on said shelf, a pivoted lever for momentarily elevating the rear end of the pile remainder, and a rear-edge sheet-engaging device movable into engagement with a forwardly-displaced sheet below the elevated end of said pile remainder and forwardly along the bottom of the pile for feeding the bottom sheet therefrom.

4. In a sheet feeding machine, the combination with means for supporting a pile of sheets including a shelf supporting the rear of the pile, a rock arm, a sheet pusher pivotally connected to said rock arm and its forward end sliding upon said shelf at the rear of said pile for imparting relative forward movements to successive bottom sheets of said pile, a pivotally mounted lever operated by said rock arm into and out of elevating engagement with the rear end of the remainder of said pile, and feed-off mechanism provided with means for engaging the rear end of the forwardly-displaced bottom sheet.

5. In a sheet feeding machine, the combi-

nation of a feed table, means for supporting a pile of sheets above said feed table, a rock-shaft, a rock-arm mounted on said rock-shaft, a sheet pusher pivotally connected to said rock-arm and movable thereby into displacing engagement with successive bottom sheets of the pile, a pivotally-mounted lever operably connected to said rock-shaft and movable thereby into elevating engagement with the rear end of the remainder of said pile, and feed-off mechanism for removing the displaced bottom sheets.

6. In a sheet feeding machine, the combination of a feed table, pile supports including front piling guides spaced from the feed table to provide a delivery throat, rear guides, and a shelf adjacent said rear guides spaced above the feed table and supporting the rear of the pile in a higher plane than the front of the pile, pushers operating above said shelf for relative forward displacements to successive bottom sheets of the pile, a pivotally mounted lever for elevating the rear end of the pile remainder, and a feed-off carrier operating above said feed table and below into the elevated rear end of the pile remainder for removing the successive bottom sheets from said pile.

7. In a sheet feeding machine, the combination of means for supporting a pile of sheets, a sheet pusher for imparting relative forward movements to successive bottom sheets of said pile, a lever mounted on a fixed axis for momentarily elevating the rear end of the remainder of said pile, a toggle link connected at one end to said lever, a second toggle link connected at one end to the other end of the first-mentioned toggle link, means for oscillating the other end of the second-mentioned toggle link about a fixed center, and a movable carrier movable into engagement with the rear end of a forwardly-displaced bottom sheet during the momentary elevation of said rear end of the pile remainder for displacing the bottom sheet from the pile.

8. In a sheet feeding machine, the combination of means for supporting a pile of sheets, a sheet pusher for imparting relative forward movements to successive bottom sheets of said pile, a lever for elevating the rear end of the remainder of said pile, a rock-shaft, a radial arm mounted on said rock-shaft and pivotally connected to said sheet pusher, a second radial arm on said rock-shaft, toggle links connecting said second radial arm to said elevating lever, and feed-off mechanism for delivering the bottom sheet from the pile.

9. In a sheet-feeding machine, the combination of a shelf for supporting one edge of a pile of sheets, means for displacing successive bottom sheets forwardly from said shelf, and a rear-edge sheet-engaging device movable into engagement with the rear edge

of said bottom sheet while the rear edge of said bottom sheet is being displaced from said shelf.

10. In a sheet-feeding machine, the combination of means for supporting a pile of sheets, a reciprocatory sheet pusher for imparting a short forward displacement to successive bottom sheets of the pile, and a continuously movable gripper movable into engagement with the rear edge of each forwardly displaced sheet during its forward displacement by said reciprocatory pusher for feeding said sheet from the pile.

11. In a sheet-feeding machine, the combination of means for supporting a pile of sheets with the rear edge of said pile higher than the front edge thereof, a reciprocatory pusher for imparting a short forward displacement to successive bottom sheets of the pile, rear-edge sheet-engaging means movable along and under the pile of sheets for removing successive bottom sheets, and means for elevating said rear-edge sheet-engaging means into engagement with the rear edge of the displaced bottom sheet during its movement across said shelf.

12. In a sheet-feeding machine, the combination with a feed-table, of a rear-edge sheet-piling guide arranged at the rear edge of said feed-table, a shelf presented forwardly from said rear-edge sheet-piling guide for supporting the rear edge of a pile of sheets, said shelf being raised above said feed-table, a slide reciprocable on said shelf for imparting forward movements to successive bottom sheets of the pile, a front-edge sheet-piling guide provided with sheet-caliper means adjustable towards and away from said feed-table, and means for adjusting said front-edge sheet-piling guide and sheet-caliper means towards and away from said rear-edge sheet-piling guide and rear-edge supporting shelf.

13. In a sheet-feeding machine, the combination with a feed-table, of a shelf elevated above said feed-table for supporting the rear edge of a pile of sheets, means for displacing successive bottom sheets forwardly upon said shelf, a rear-edge sheet engaging device for moving a sheet over said feed-table, and means for momentarily elevating said rear-edge sheet-engaging device above said shelf and into engagement with the rear edge of the bottom sheet as said sheet-engaging device passes said shelf.

14. In a sheet-feeding machine, the combination of means for supporting the rear edge of a pile of sheets at a higher elevation than the front edge thereof, a reciprocatory sheet pusher for imparting a short forward displacement to successive bottom sheets of the pile, and a continuously movable gripper operating below said pile of sheets and movable into engagement with the rear edge of each forwardly displaced sheet during its forward displacement by said reciprocatory

pusher for feeding said sheet from the pile.

15. In a sheet-feeding machine, the combination of means for supporting a pile of sheets with the rear edge of said pile higher than the front edge thereof, a rear-edge sheet-piling guide, a reciprocatory pusher movable past said rear-edge sheet-piling guide for imparting a short forward displacement to successive bottom sheets of the pile, a front-edge sheet-piling guide adjustable towards and away from said rear-edge sheet-piling guide, and means movable into engagement with each displaced bottom sheet during the time it is supported by said supporting means for feeding-off successive bottom sheets to which the said short forward displacements have been imparted.

16. In a sheet-feeding machine, the combination of a shelf for supporting one edge of a pile of sheets, means for displacing successive bottom sheets forwardly from said shelf, means for elevating the rear edge of the remainder of said pile of sheets after the forward displacement of each successive bottom sheet of the pile, and a rear-edge sheet-engaging device movable into engagement with the rear edge of said bottom sheet while the rear edge of the remainder of said pile is elevated and as said bottom sheet is being displaced from said shelf.

17. In a sheet-feeding machine, the combination of a rear-edge guide for a pile of sheets, said rear-edge guide being provided with means for supporting the rear edge of a pile of sheets, a reciprocatory sheet pusher for imparting a short forward displacement to successive bottom sheets of the pile, a gripper movable into engagement with the rear edge of each forwardly displaced sheet during its forward displacement by said reciprocatory pusher for feeding said sheet from the pile, a front-edge guide for said pile of sheets, and means for adjusting said front-edge guide towards and away from said rear-edge supporting means.

18. In a sheet-feeding machine, the combination of means for supporting a pile of sheets with the rear edge of said pile higher than the front edge thereof, a reciprocatory pusher for imparting a short forward displacement to successive bottom sheets of the pile, an endless conveyor movable beneath said pile from rear to front, a rear-edge sheet gripper mounted on said conveyor, means for operating said gripper to engage the rear edge of successive bottom sheets, and means for driving said conveyor and reciprocating said pusher, the last-mentioned means being adapted to co-ordinate the movements of said gripper to transfer a sheet from said pusher to said gripper midway of the forward movement of said pusher.

19. In a sheet-feeding machine, the combination with a feed-table, of a rear-edge pile-support arranged above and adjacent to the

rear edge of said feed-table, a rear-edge pile-guide extending upwardly and away from said rear-edge pile-support, means movable into engagement with the rear edges of successive bottom sheets of the pile for imparting short forward movements thereto, sheet feeding means including a device for engaging the rear edge of each successive sheet, said rear-edge sheet-engaging device being movable past said rear-edge pile support,
5 means for raising said rear-edge sheet-engaging device as it passes said rear-edge pile-support, a front-edge pile-guide having its lower edge spaced from said feed-table to form therewith a sheet-controlling delivery throat, a sheet-caliper gate-member carried by said front-edge pile-guide, and means for adjusting said front-edge pile-guide towards and away from said rear-edge pile
10 guide.
